WAVE FILTER

Leslie F. Curtis, Springfield, Mass., assignor to
United American Bosch Corporation, Springfield,
Mass., a corporation of New York

Application June 27, 1936, Serial No. 87,711

4 Claims. (Cl. 178—44)

This invention relates to radio apparatus and more particularly to a tuned filter circuit for eliminating an undesired frequency from a band of transmitted frequencies.

In the past, filters of various kinds have been employed in the antenna circuit of radio receivers to minimize the effect of interfering stations and were commonly known as "wave traps". In the smaller types of superheterodyne receivers the antenna is connected to the first detector stage and no intervening stage of tuned radio frequency is employed. In such receivers an interfering signal at or near the frequency to which the intermediate frequency amplifier is tuned will be transmitted directly through the first detector to the intermediate frequency amplifier. Since 465 kilocycles has become almost a standard tuning frequency for the intermediate amplifier, the interference is usually code transmission from stations handling ship to shore traffic and operating on frequencies near 465 kilocycles. While filters according to the prior art practice reduced the interference from a particular station, the interfering signal was not eliminated and the reproduction of a desired program suffered accordingly.

It is therefore one of the objects of this invention to provide a filter circuit which shall be more effective in blocking a given transmitted frequency.

Another object is to provide a filter circuit which may be included in the receiver construction or may be in the form of a separate unit.

Still another object is to provide a filter unit which is more stable in construction and requires less frequent adjustment.

A further object is to provide a filter unit which is more compact in structure and economical in assembly.

Other objects and advantages will in part be specifically stated and in part be obvious when the following specification is read in connection with the drawings, in which:

Fig. 1 is a schematic diagram of the filter; Fig. 2 is a top view of the filter assembly; Fig. 3 is a section taken on line 3—3 of Fig. 2; and Fig. 4 is a bottom view of the filter assembly.

Referring in more detail to Fig. 1, the numeral 1 indicates any suitable antenna. A series resonant circuit comprising an inductance 2 and a variable condenser 3 is connected between the antenna and ground. A parallel resonant circuit comprising inductance 4 and variable condenser 5 is connected in series with the antenna 1 and to the antenna post of a receiver 6. An electro-

static shield 7 may be used if necessary to eliminate undesired electrostatic coupling between the inductance 2 or condenser 3 and the output terminals of the device. The inductances 2 and 4 are magnetically coupled and one of the inductances is movably supported to provide a variable coupling between the inductances, as will later be shown and explained in detail.

In Fig. 2 there is shown a top plan view of the component filter elements as arranged on an insulating base. The reference numerals indicating the diagrammatic showing of the parts in Fig. 1 will be applied to like parts in Fig. 2 and the following figures.

The assembly is mounted upon a base 8 which may be a disk of any suitable insulating material such as one of the synthetic resins. Attached to the base 8 by means of mounting bolts 9 and nuts 10 is double alignment condenser of the type commonly used in intermediate frequency transformers. The double alignment condenser comprises a ceramic base 11 upon which is mounted compression type variable condensers 3 and 5 which may be adjusted by the compression screws 14 and 15 respectively. The condenser 5 has terminals 16 and 17 which project upwardly through slots in the ceramic base 11, and the condenser 3 has similarly arranged terminals 18 and 19. A bow spring 20 of non-magnetic material is secured to the ceramic base 11 by means of the mounting bolts 9 and extends transversely over the base 11 as best seen in Fig. 3. A longitudinal slot is provided in the bow spring 20 through which projects a tongue 21 on the coil form supporting the inductance 4. Secured by a mounting bolt 9 and extending angularly from the ceramic base 11 is a coil bracket 22 of sheet metal which supports the coil form 23 and inductance 2. The inductances 2 and 4 are each universal wound and in two sections as illustrated by the inductance 2 of Fig. 2.

In Fig. 3 is shown a cross section of the device taken on line 3—3 of Fig. 2. The movable inductance 4 is adjusted by the screw 24 which is carried by a threaded opening in the mounting strip 25. A metal shell 26 having a mounting bracket 27 is spun over and secured to the insulating base disk 8.

Fig. 4 is a bottom view of the device showing the condenser adjusting screws 14 and 15 accessible through an opening in the base disk 8. The mounting strip 25 is secured by the screws 9 and extends transversely across the opening in the disk 8, carrying the centrally located coil adjusting screw 24.

In the operation of the device, the series circuit comprising inductance 2 and capacity 3 and the parallel circuit comprising inductance 4 and capacity 5 are both tuned approximately 5 to the interfering frequency which is to be eliminated. Even though the circuits are tuned exactly to the undesired frequency, there will be a residual voltage at this frequency due to the radio frequency resistance of the inductances 2 and 4. 10 By suitable regulation of the mutual coupling between the inductances, the residual voltage in the respective circuits may be made to cancel out and the terminal voltage at the interfering frequency will be reduced to substantially zero. 15 When the circuits are slightly off tune with the interference, the voltage thereof may still be reduced to zero by the adjustment of coupling. Inductances having a relatively poor power factor may be employed in this present device and 20 so reduce the expense of parts, whereas in the prior art devices their effectiveness depended upon the reduction of the power factor to the lowest possible values. In tests it has been found that an interfering signal can be reduced 25 on the order of 30:1 or slightly better by the proper adjustment of coupling, over the reduction possible with the same circuits without the mutual coupling between inductances.

It will be obvious that many uses and special 30 applications of the invention exist, other than the particular one illustrated and described. Likewise, many changes and modifications may be made in the invention by any one skilled in the art without departing from the spirit and 35 scope of the invention as set forth in the following claims:

I claim:

1. In a filter circuit for the attenuation of a predetermined frequency, a shunt impedance arm tuned to said frequency and having a residual voltage of said frequency across the terminals thereof, a series impedance arm tuned to 40 said frequency and having a residual voltage

of said frequency differing in phase from the residual voltage of said shunt impedance arm, and means for establishing a mutual coupling relation between said impedance arms, whereby said residual voltages may be substantially eliminated. 5

2. In a filter circuit for the attenuation of a predetermined frequency, a shunt impedance arm comprising a series resonant circuit tuned to said frequency and having a residual voltage of 10 said frequency across the terminals thereof, a series impedance arm comprising a parallel resonant circuit tuned to said frequency and having a residual voltage of said frequency differing in phase from the residual voltage of said shunt 15 impedance arm, and means for establishing a mutual coupling relation between said impedance arms, whereby said residual voltages may be substantially eliminated.

3. In a filter circuit for the attenuation of a 20 predetermined frequency, a shunt impedance arm tuned to said frequency and having a residual voltage of said frequency across the terminals thereof, a series impedance arm tuned to 25 said frequency and having a residual voltage of said frequency differing in phase from the residual voltage of said shunt impedance arm, and means for combining said residual voltages in one of said impedance arms, whereby they may be substantially eliminated. 30

4. In a filter circuit for the attenuation of a predetermined frequency, a shunt impedance arm tuned to said frequency and having a residual voltage of said frequency across the terminals thereof, a series impedance arm tuned to 35 said frequency and having a residual voltage of said frequency differing in phase from the residual voltage of said shunt impedance arm, and means for impressing upon the shunt impedance arm the residual voltage existing across said 40 series impedance arm, whereby the residual voltage may be substantially eliminated.

LESLIE F. CURTIS.
